TOBACCO PIPE

Louis Goldvogel and George St. John, New York,
N. Y., assignors to D. A. Schulte, Inc., New York,
N. Y., a corporation of New York

Application April 11, 1939, Serial No. 267,229

4 Claims. (Cl. 131—184)

Our invention relates to pipes for smoking tobacco and has reference particularly to certain improvements in a removable cleaning and absorbing fitting for the smoke passage of the pipe.

The objects of our invention are first to provide a cleaning attachment removably carried by and projecting from the mouth piece into the smoke passage of the pipe stem; second, to provide a chamber in the cleaning attachment in communication with the smoke passage to receive and to retain therein, while the pipe is being smoked, a removable brush-like element to filter out and absorb a very substantial quantity of the nicotine and moisture passing with the smoke from the bowl of the pipe to the mouth piece; and third to afford a mouth piece having a split tenon to removably support the cleaning attachment.

We accomplish the objects of our invention by means of certain structural features, one embodiment of which is described in the following specification, set forth in the appended claims and illustratively exemplified in the accompanied drawing in which:

Figure 1 is substantially longitudinal sectional view of a tobacco pipe embodying my improved cleaning attachment;

Figure 2 is a substantially transverse sectional view of the pipe stem and cleaning attachment taken on lines 2—2 of Figure 1;

Figure 3 is a substantially longitudinal sectional view of the cleaning attachment which is shown on a somewhat enlarged scale;

Figure 4 is a side elevational view of the cleaning attachment; and

Figure 5 is an end elevational view of the attachment.

Referring now to the details of construction, illustrated in the drawing, the pipe comprises a bowl 10 and shank or stem 11, the latter having a uniform bore or smoke passage 12, and being connected to a bit or mouth piece 13 having a bore 14 forming a continuation of the passage 12. The mouth piece is removably united with the stem 11 by means of a union 15, comprising a tube provided with an annular flange 16 at its mid portion. The tube at its inner end 17 is permanently mounted in the bore 14 and one face of the flange 16 abuts the end of the stem, the other end of the tube projecting from the mouth piece forms the tenon 18. The tenon 18 is cut on opposite sides and longitudinally thereof to form slits 19.

The cleaning attachment 20 is removably carried in the split tenon 18 and comprises a cylindrical metal fitting provided with four longi-

tudinally disposed grooves 21 running from the end held in the tenon 18 to a point just short of the opposite end. The grooves 21 are evenly spaced about the surface of the fitting, and between adjacent grooves the material of the fitting forms longitudinal ribs 22. Each of the four ribs 22 is stepped down slightly at the end of the fitting which is held by the tenon 18 to form a circumferential shoulder 23 against which the end of the tenon abuts when the fitting is fully inserted. Each groove 21 communicates with the space in the smoke passage 12 beyond the fitting through a small orifice 24 in the end wall thereof. And each groove 21 is in communication with the bore 25 of the fitting by means of a slot 26 in the bottom of the groove, each slot having a longitudinal dimension substantially shorter than the distance between the closed end of the slot and the shoulder 23 of the ribs 22. The diameter of the fitting 20 is slightly less than the diameter of the smoke passage 12 in the stem 11 so as to provide a loose fit between the two parts, the fitting being actually supported in the passage by means of the tenon 18 which fits very snug in the stem.

Moisture and nicotine, which gather in the smoke passage and in the grooves 21 when the pipe is smoked, are conveyed to the interior of the fitting 20 through the slots 26, and are picked up and absorbed in the brush portion 27 of a removable cleaner disposed within the bore of the fitting. The brush-like cleaner 27 is mounted upon a wire stem 28 and the bristles project radially through the slots 26 and into the grooves 21, the stem 28 projecting outwardly through the open end of the bore and into the union 15, as illustrated in Figure 1.

In use the smoke from the bowl 10 is drawn into the smoke passage 12 in the stem 11 where it contacts the closed end of the fitting 20, enters the orifices 24 thereof and passes along the grooves 21 between ribs 22 into the tenon 18 and then through the bore 14 of the mouth piece 13. The walls of the ribs 22 cause the moisture in the smoke to condense and collect in the grooves. The moisture is then picked up by the brush-like cleaner which may be removed and discarded if necessary. The entire fitting also acts as a cleaner by simply turning the mouth-piece on the stem and with it the fitting, whereupon the peripheral wall of the ribs will engage and detach any amount of residue which may have collected on the wall of the smoke passage.

What we claim is:

1. A smoking pipe, comprising a bowl and stem, 55

and a mouth piece removably fitted in the stem, and a cleaning attachment removably carried by the mouth piece comprising an exteriorly grooved tubular fitting provided with a closed free end 5 having orifices, each orifice communicating with a groove, and slots in the bottoms of the grooves to communicate with the bore of the fitting, said slots extending between points spaced from the ends of the grooves, and a brush-like member 10 removably disposed in the slotted portion of the bore.

2. A smoking pipe, comprising a bowl and stem and a mouth piece, a union fixed in the mouth piece and provided with a longitudinally split 15 tenon to removably engage and fit the bore of the stem, and a cleaning attachment for the stem comprising an externally and longitudinally grooved tubular fitting which is closed at the free end and provided with orifices in the closed end 20 opening into the grooves, and which is further provided with slots in the bottoms of the grooves to form communications between the grooves and the bore of the fitting, said slots extending between points spaced from the ends of the grooves, 25 the open end of the fitting being removably em-braced by the split tenon, and a brush-like ele-ment in the slotted portion of the bore to project radially through said slots, said element having a stem projecting beyond the open end of the fit-30 ting whereby the element may be removed there- from.

3. A smoking pipe, comprising a bowl and stem having a smoke passage, and a mouth piece provided with a split tenon removably fitted in the stem and cleaning means for the bore of the stem removably carried in the split tenon comprising 5 a cylindrical metal fitting having longitudinally disposed grooves projecting from the end in said tenon to a point short of the opposite end and opening into orifices in the latter end, the mate-rial between the grooves forming ribs which fit 10 loosely in the bore of the stem, said grooves being provided with slots in the bottoms thereof open-15 ing into an axial bore in the fitting, said bore being closed beyond the ends of the slots adja-ent the closed ends of the grooves, and a brush-like member having radial bristles at one end in-10 serted into the bore of the fitting in the region of the slots through which they project into the grooves and a stem portion projecting beyond the open end of the fitting whereby the brush-like 20 member may be withdrawn from the fitting.

4. A cleaning attachment for a pipe as claimed in claim 3, in which the end of each rib inserted in the split tenon is stepped down substantially less than the depth of the grooves to form a 25 shoulder to abut the end of the said tenon, where-20 by the grooves extend through to the end of the fitting.
